Primary Examiner — George D Kirschbaum*Assistant Examiner* — Kendra L Hamilton(74) *Attorney, Agent, or Firm* — Knobbe Martens Olson & Bear LLP(57) **CLAIM**

The ornamental design for a lid, as shown and described.

DESCRIPTION

FIG. 1 is a top, front and side perspective view of a lid embodying the new design.

FIG. 2 is a first side view thereof.

FIG. 3 is a second side view thereof; and,

FIG. 4 is a front view thereof, the back being a mirror image. Broken lines illustrating threads on the lid form no part of the claimed design. Portions of the underside of the lid not shown in the drawing form no part of the claimed design.

1 Claim, 3 Drawing Sheets---
